CLAIM

The ornamental design for a display screen with graphical user interface, as shown and described.

DESCRIPTION

The file of this patent contains at least one drawing executed in color. Copies of this patent with the color drawing will be provided by the Office upon request and payment of the necessary fee.

The FIGURE is a front view of a display screen with graphical user interface showing my new design.

The broken line illustrating a display screen forms no part of the claimed design. The remaining broken lines and the area within illustrate portions of the graphical user interface which form no part of the claimed design.

1 Claim, 1 Drawing Sheet
